CLAIM

USPC **D9/519**; D9/666

The ornamental design for a confectionery packaging with wrapping sheet as shown and described.

(58) **Field of Classification Search**

DESCRIPTION

USPC D9/452, 453, 500, 501, 502, 503, 504,

1. Confectionery packaging with wrapping sheet
Figures 1.1, 1.2, and 1.3 show front view, top view, and
bottom view, respectively, of a confectionery packaging
with wrapping sheet.

D9/505, 516, 523, 529, 544, 545, 546,

The gray-tone hatching features shown on the article repre-
sent a contrast in appearance. The de-emphasized area in
